UNITED STATES PATENT OFFICE.

WILTON H. PERRY, OF BROOKLYN, NEW YORK.

BOTTLE FOR HOLDING MUCILAGE AND LIKE ADHESIVES, AND COMBINED BRUSH AND STOPPER THEREFOR.

Application filed February 29, 1924. Serial No. 695,921.

The objects of my invention are to provide a closed receptacle or bottle, for use as a desk-bottle for holding a liquid adhesive of mucilaginous characteristics; which bottle whether 5 of my new and improved form, or of any old and well known form, is provided with a combined spreading device, usually and preferably of the well known bristle-brush form, and bottle-mouth stopper; which stopper- 10 portion is formed of any suitable bibulous material which will absorb and retain water, such for instance as, for example sea-sponges, rubber-sponge, felt, bibulous paper, etc., which when dipped in water will immediately 15 take up and absorb a large portion thereof, and will hold and retain the same for a long time, but keeping the air enclosed in the bottle cut off from the free outside air, practically in a state of vaporous saturation; and 20 thereby preventing the mucilage or other adhesive within the bottle from thickening up, and drying out, either on the walls of the bottle, or on the brush; whereby such mucilage is kept at all times in such a liquid state, 25 as to be ready for instant use.

My said invention is fully shown described and claimed in the following specification, of which the accompanying drawing forms a part, wherein similar numerals of reference 30 designate like or equivalent parts wherever found thruout the several views, and in which:—

Figure 1, is a front view in elevation, taken in central vertical section, of a mucilage or adhesive holding bottle of my new and improved form; having one of my new and improved combined brush and bibulous-stopper, in position therein, so as to cut off the outer air from access to the interior of such desk bottle; Fig. 2, is a similar view of an old and well known type of bottle long in use, for the holding of mucilage and other adhesives, showing such bottle closed from the outer air by one of my combined mucilage-brush and 45 bibulous bottle stoppers, of a somewhat modified form of construction from the form shown in Figs. 1 and 3, and Fig. 3, is a similar view in central vertical section, of another modified form of bottle, and my improved 50 bibulous stopper, and combined brush or dauber therefor.

Referring to the drawing:—

In the particular form in which I prefer to embody my said invention, shown in Fig. 55 1, the bottle itself is of my new and improved

form shown, blown or pressed to shape in a suitable mold from glass in a fluid and molten state; and such bottle is preferably provided at the center of its bottom 1, with an upwardly and inwardly extending central hump or 60 boss 2, with which the bristle or brush end 3, of the combined brush and stopper of my new and improved form is normally in contact.

Such bottle may be of any suitable size, shape and contour, but is usually and preferably of the rounded shape shown in such Fig. 1, and having its central brush orifice 4, encircled by an outer annular flange-receiving chamber or channel 5, the outer-wall of the mouth of such bottle, being preferably belled 65 outward by the gently curved portion of such wall indicated at 6, in order to make such mouth larger to receive a bibulous stopper holding more water. But such mouth however usually and preferably ends in the 70 straight upwardly extending wall-portion 7, usually and preferably provided on top of its annular top-edge with a ground or sand-blasted, or otherwise roughened end surface, so as to make practically an air-tight seal be- 75 tween such roughened surface, and the inner abutting surface of the top-cap disk 8. And such top-cap 8, is usually and preferably, but not necessarily in all cases made of suitable wood turned to form as shown and 80 colored or painted by dipping and drying, in the well known manner; and the same is usually and preferably provided at its outer peripheral edge with the downwardly de- 85 pending annular flange 9, which in combina- 90 tion with the ground end surface of the outer-wall of such bottle, will form a practically air-tight seal between them, to conserve the moisture in the bibulous and water retaining stopper 10.

Such top-cap 8, has secured thereto the central upwardly extending handle 11, having at its bottom central small cylindrical brush carrying and securing-lug portion 12, by which it is firmly cemented to the top-cap 95 8; which lug portion 12, also carries at its extreme lower end the metallic brush-sleeve 13, carrying the bunch of bristles 3, which compose the brush by which the mucilage is spread upon the sheets of paper, etc., to be 100 105 adhesively secured together.

In the modified form of construction of bottle and stopper shown in Fig. 3, the same differs from that shown in Figs. 1 and 2, in that the main wall of the bottle instead 110

of being curved or belled outward as in Fig. 1, is shown as straight, altho it may be made of belled or any desired other shape, but in any event, such outer annular wall is provided at its upper and mouth-end of the bottle-wall, with an annular outer circumferential flange-receiving chamber 5' (similar to the like chamber 5, of Fig. 1,) in which lies the annular ring or washer 16', which in Fig. 3 is formed in a single piece, of the same water retaining absorbent bibulous material as is the stopper 10', which in such Fig. 3, is however entirely separated from the washer, flange, or ring 16', instead of being formed integral with the main and upper portion of the stopper 10, as it is shown in Fig. 1, at 16. And in such Fig. 3, both the inner and the outer upwardly extending walls of the annular washer receiving-chamber 5', are of the same length, and are each preferably roughened at the extreme outer ends thereof, as is only the longer upper outer wall of the bottle-mouth, in Fig. 1, as and for the same reasons, so as to in Fig. 3, provide a tight-seal between such top-ends of such annular chamber 5', and the inner absorbent and bibulous water retaining stopper 10', of this particular construction, which is as shown, usually but a thin annular sheet of such absorbent bibulous water retaining material. And in this construction shown in Fig. 3, it will be seen that that such washer 16', is normally retained in its annular chamber, and is never removed therefrom, altho it may be when it is desired to saturate it anew with water; but this may be done by merely pouring water slowly upon it, while it still remains in its annular chamber; and thus at all times such washer or ring 16', acts as a water reservoir which always keeps the air in the bottle so moist as to prevent the mucilage or other adhesive from drying out.

In Fig. 2, I have shown a mucilage bottle of an ancient and well known form of construction, with an air-lock reservoir, by the use of which most of the mucilage is normally in the bell, and only a small surface of the mucilage is in contact with the atmosphere; and in such Fig. 2, I have shown such well known form of air-lock bottle provided

with a mouth-stopper 10², of suitable shape to close and seal the mouth thereof, which stopper and combined brush or dauber, has its mouth-stopper portion 10² formed of any of the enumerated bibulous water retaining and absorbing materials hereinbefore referred to.

Of whatever material my improved bibulous water retaining stopper may be composed, the same is so shaped by moulding, trimming, or in any other suitable way, into any of the several forms shown to fit any suitable bottle, and, to prevent entrance to the mucilage while the combined brush and stopper of my improved form is in place in such bottle-mouth of any dry air from outside; while keeping the air within such bottle and in contact with the mucilage, in a very moist state.

I do not intend to in any manner limit myself strictly, to the exact form of construction, of the mucilage bottles shown, nor to the exact number, or arrangement of parts of my improved brush and stopper for mucilage bottles shown and described; as it is evident that such constructions may be widely varied in many ways, without in any manner departing from the broad scope of my invention.

I claim:

1. A mucilage desk-bottle having within its mouth orifice an outer annular chamber open at the top; in combination with a combined brush and bottle-stopper, the stopper portion of which is formed of bibulous water absorbing material, so shaped as to completely fill and fit closely in the mouth of such bottle, including such annular-chamber at its mouth.

2. A bottle having within its mouth an annular chamber open at the top, in combination with a stopper formed of bibulous water absorbing material and shaped to substantially fill the mouth of the bottle and the annular chamber formed therein.

Signed at the county of Kings, borough of Brooklyn, city and State of New York, U. S. A.; this 27th day of February, A. D. 1924.

WILTON H. PERRY.
